UNITED STATES PATENT OFFICE.

KÁROLY PAP, OF KOLOZSVÁR, AUSTRIA-HUNGARY.

AUTOMATIC-SHUT-OFF WATER-GAGE.

1,072,642.

Specification of Letters Patent. Patented Sept. 9, 1913.

Application filed August 1, 1912. Serial No. 712,683.

To all whom it may concern:

Be it known that I, KÁROLY PAP, a subject of the King of Hungary, and resident of Kolozsvár, Austria-Hungary, have invented certain new and useful Improvements in Automatic-Shut-Off Water-Gages, of which the following is a specification.

The present invention relates to certain new and useful improvements in the construction of water-gages, such as are commonly employed in connection with steam boilers.

One of the defects of the water-gages heretofore in use is that the height of the water in the boiler can be observed only by those who are standing very close to the water-gage, and another defect of most of the devices consists in that the stokers or firemen are liable to be injured by the escaping steam and hot water in case the glass of the water-gage is broken.

It is one of the objects of the present invention to provide a simple and inexpensive water-gage, by means of which the level of the water in the boiler may be observed within a substantial distance from the boiler, and furthermore to produce an automatic safety shut-off, whereby, as soon as the glass of the gage is broken, the supply of steam and water is automatically shut off therefrom.

With these and other objects in view, which will more fully appear as the nature of the invention is better understood, the same consists in the combination, arrangement and construction of parts hereinafter fully described, pointed out in the appended claim and illustrated in the accompanying drawings, it being understood that many changes may be made in the size and proportion of the several parts and minor details of construction within the scope of the appended claim without departing from the spirit or sacrificing any of the advantages of the invention.

One of the many possible embodiments of the invention is illustrated in the accompanying drawings, in which:—

Figure 1 is a vertical longitudinal section taken through a safety water-gage constructed in accordance with the present invention; and Fig. 2 is a front elevation of the dial of the same.

In the drawings, the numeral 1 indicates the head of a boiler, and the numeral 6 a closed receptacle, which communicates by

means of pipes 2 and 3 with the interior of the boiler. The pipe 2 leads to the steam space and the pipe 3 to the water space of the boiler. Into these pipes are inserted 60 valves 4 and 5, respectively, for a purpose hereinafter to be described. Within the receptacle 6 is arranged a hollow, preferably, metallic float 7, the upwardly projecting extension 9 of which is slidably arranged in 65 guides 11, 11 upon the interior surface of the casing 6. The upper end of the casing 6 is provided with a cylindrical enlargement 14, which is provided upon its outer face with a graduated dial 15. The upper 70 end of the extension 9 of the float is provided with a rack 10, the teeth of which are adapted to mesh with those of the gear segment 12, which is keyed or otherwise attached to a spindle 13, the latter being oscillatably arranged in the front wall of the enlargement 14 and projecting therethrough. To the spindle 13 is attached a hand 16, pointing to the graduations of the dial 15.

The casing 6 is provided in its front wall 17 with a window, which is closed by two panes of glass 18 and 19, or other suitable transparent material, said window-panes being arranged at a substantial distance 85 from each other. A pipe 21 leads from the space between the two window-panes 18 and 19 to the head of a steam cylinder 22, which latter is attached to the boiler head or to any suitable support. Within the cylinder 90 22 is reciprocably arranged a piston 23, the piston rod 24 of which is pivoted to a connecting rod 25, the latter being in a similar manner attached to a lever 27, which is keyed or otherwise attached to the plug of 95 the valve 4. A link 26, pivoted to the connecting rod 25, is in a similar manner secured to a lever 28, which is rigidly connected with the plug of the valve 5.

The operation of the device is as follows: 100 As the level of the water in the boiler varies, the float 7 will accordingly rise or fall, and actuate thereby the hand 16 above described. The level of the water in the boiler can thus be observed from a distant point 105 by examining the positions of the hand 16. If for some reason the inner one of the window-panes, that is the pane 18, should be broken, steam will escape through the pipe 21 into the cylinder 22, act upon the 110 piston 23 and thereby shut off automatically steam and water from the casing 6.

What I claim is:—

In a water-gage for boilers, the combination with a closed receptacle communicating with the steam and water spaces of a boiler 5 provided with a window closed by two transparent panes which are arranged at a distance from each other, of a hollow float in said receptacle, a graduated dial, a hand oscillatably mounted upon said receptacle 10 pointing to the graduations of the said dial, coöperating means upon said float and said hand for actuating the latter upon the rising and falling of the float in said recep-

tacle, valves controlling the communications between the boiler and said closed receptacle, a steam cylinder, a piston therein, a connection between said piston and said valves, and a steam pipe leading from the space between said two window-panes to said cylinder. 15

Signed at Budapest, Austria-Hungary, this 19th day of July, A. D. 1912. 20

KÁROLY PAP.
